(57) **CLAIM**

The ornamental design for an electrical connector, as shown and described

DESCRIPTION

FIG. 1 is a front elevational view of an electrical connector, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, top and right side perspective view thereof; and,

FIG. 8 is a rear, bottom and right side perspective view thereof.

The broken line portion of the figure drawings is included to show unclaimed subject matter only and forms no part of the claimed design.
